UNITED STATES PATENT OFFICE.

ALBERT F. NATHAN, OF PLAINFIELD, NEW JERSEY.

MITER-CURVE CUTTER.

1,406,481.

Specification of Letters Patent. Patented Feb. 14, 1922.

Application filed June 26, 1918. Serial No. 242,045.

To all whom it may concern:

Be it known that I, ALBERT F. NATHAN, a citizen of the United States, and residing at Plainfield, in the county of Union and State 5 of New Jersey, have invented a new and Improved Miter-Curve Cutter, of which the following specification is a full disclosure.

This invention proposes a mechanism suitable for cutting sheet-metal into "elbow sections" of large dimensions; i. e., for cutting so-called "miter-curves". Heretofore, this has been done either by means of hand-shears, or by one or the other of the machines described in the U. S. Patents Nos. 729,964 10 and 730,874 issued to Scherer and to Chambers and Bullard, respectively. Both of these machines depend upon a single track to direct the movements and control the positions of the cutters; the carriage (on 15 which the cutters are supported) in each case is held on the track by two pairs of horizontal rollers on the erroneous supposition that a line connecting the pairs will be maintained parallel to a tangent at the various 20 stations along the curve. It may also be noted that, owing to the continually varying radius of the miter-curve, the four rollers cannot geometrically be constantly in rolling-contact with the track. Consequently, 25 they must provide sufficient "lost-motion" or "back-lash" to prevent binding at stations demanding the widest separation. Any departure from the true tangent creates a "draw" in the line being cut, and any lost 30 motion causes a divergence from the line of the miter-curve.

The object of this invention is to create a mechanism, based on geometrically correct principles, which will so guide the cutters 35 as to maintain their cutting-point accurately coincident with a true miter-curve, and at the same time invariably maintain the cutting-plane (direction of cut) precisely tangent to the curve.

40 This may best be explained in connection with the drawings, of which; Fig. 1, is a geometrical lay-out of this invention; Fig. 2, is a side elevation of a practical embodiment thereof; while Fig. 3, is a plan of the ma- 45 chine.

Let D—E—F— c'' represent in elevation a cylinder corresponding in diameter to the pipe-section for which an "elbow" is to be made. A—B is the trace of a plane cutting 50 it at the angle desired for the joint of the "elbow"; said angle being 15° in this in-

stance. The semi-circle H—O—11" represents a plan of half the cylinder. It may be shown that the entire miter-curve consists of four identical sections disposed 60 reversely and in opposition respectively. Hence it will suffice to describe the lay-out for one quadrant of the curve; e. g., the portion within the rectangle M—O—11—N, in length equal to $\frac{\pi r}{2}$. Since $\pi = \frac{22}{7}$, the length 65 of O—11 will be $\frac{11}{7}r$. Hence, divide the radius K—11" into seven equal parts, and lay out eleven of these on the 70 quadrant-circle, as 1", 2", 3", 4", etc., and also develope these as points 1', 2', 3', 4', etc., along the line O—11. Each of the eleven verticals from these points will intersect the corresponding one of the eleven 75 equi-spaced horizontals (between O—O on line M—K) at the stations O, 1, 2, 3, 4, etc. on the "miter-curve" shown in dotted lines. In this manner, the miter-curve is accurately 80 defined.

It now becomes necessary to locate the tangents for these stations. Take station 6", for example. Draw the tangent $c^6—6''$ — c^6 through the point 6" on the quadrant-circle O—6"—11". This may be very accurately done by drawing a radius from K bisecting the angle O—K—6"; and another radius bisecting the complementary angle 6"—K—11. The intersections of these radii with the horizontal and vertical lines 85 through c^6 , accurately locate the points c^6 and c^6 . About c^6 as a center, draw the arc $c^6—c^6$; the latter point being its intersection with the horizontal. Drop a vertical from c^6 and note where it intersects the cutting-plane A—B. A line drawn through these last located points c^6 and c^6 will be parallel to the tangent to be drawn through the station 6" on the miter-curve. Therefore, draw 90 such tangent $6x—6''—6z$. Another way is 100 to locate the point t^6 on the horizontal D—O by measuring $6'—t^6$ equal to $6''—c^6$. Then, a line drawn through 6 on the miter-curve and t^6 will be the tangent to the miter-curve 105 at the station 6.

In this manner, tangents may be drawn at each of the stations 1, 2, 3, 4, 5, 6, etc., for all points of the miter curve. It may be noted, however, that the labor of developing each tangent in the manner aforesaid 110 may be greatly curtailed by observing that the miter curve is composed of four identical

sections; each section being similar to that corresponding to a quadrant of the circle; i. e., similar to the portion of the curve within the rectangle O—11—N—M. The 5 tangents for the various other sections of the curve can, therefore, be obtained merely by duplicating the tangents in the aforesaid rectangle in each of the other three corresponding rectangles. For example, the layout in 10 the rectangle T—O—M—P is exactly that above described, the only difference being that the latter rectangle is produced by rotating the first rectangle bodily through an angle of 180° in the plane of the paper. 15 Likewise, the layout for the rectangle to the right of that first named is obtained by rotating the rectangle O—11—N—M bodily through 180° about the line 11—N as an axis.

We have now obtained all of the tangents 20 throughout the length of the curve. The proposition now reduces merely to the development of two tracks, each of which is the locus of a point having a fixed definite relation to the tangent. Preferably, as a 25 matter of convenience in layout, points are selected equally distant from the centre of the tangent; i. e., its point of contact with the miter curve. Thus, a point 6^x is the same distance to the left of the point 6 as the point 6^z is to its right. By laying out 30 these various points on the various tangents, we obtain a curve shown in dashes and indicated by the points O^x, 1^x, 2^x, 3^x, etc., for the left hand end of the tangent; and a 35 similar curve O^z, 1^z, 2^z, 3^z, etc., for the right hand portion of the tangent.

It will now be evident that if the aforesaid dotted curves could be used as tracks, and if the above defined points on the tangent could be maintained in coincidence with said curves, then they would serve to maintain the centre of the tangent in coincidence with the dotted miter curve, and would also keep the tangent truly tangential to the 45 curve at all of its stations of contact. Accordingly, if a carriage could be arranged in fixed relation to the travelling tangent so as to be guided and located thereby, then such carriage could be used for supporting and 50 guiding suitable conventional rotary cutters such as are employed in the shearing of sheet metal. Such cutters, however, if mounted on the carriage so as to be vertical from the point 6, when the carriage is in the position shown in dotted lines and when the axes of the cutters are in the vertical plane of the line S—G, then will the cutters be caused not only to trace the miter curve in 55 true coincidence therewith but also to be accurately tangential thereto at all points of contact. Accordingly, the sheet metal, by such a mechanism, must necessarily be cut “true to pattern” and without any “draw” of the metal.

65 If it be desired to use the aforesaid loci

directly as tracks, it will be observed that they must be arranged in different planes on account of the fact that these curves cross. In fact, one curve is virtually the same as the other save for being translated in the 70 direction of the line X—X. It may be more convenient, therefore, to arrange the tracks in the same plane and this can readily be done by striking an arc about 6 as a center from the points 6^x and 6^z. At 75 definite distances from these points 6^x and 6^z are located the centers of similar rollers Z and Z'.

In putting this invention into practical effect, a rotary shearing mechanism of a 80 conventional type will be provided with two sets of guide rolls for the two guideways or tracks, respectively. Means will be provided for clamping a blank of sheet metal to hold it under the action of the cutters. 85 The mechanism may be conveniently arranged on a bench, such as indicated by C, which provides an upper table or platform I and a lower shelf J. On this lower shelf is mounted a plate or frame L provided with 90 a dual track W—W' and any suitable fastening means such as the bolts a may be employed to hold it onto said shelf. The rotary shears consist of the usual U-shaped casting Q, through the upper and lower legs 95 of which extend shafts supporting the rotary cutters b and c at the one end and the gears d and e at the other end; a hand crank f being used to impart rotation to the shears. The casting Q is mounted on a base extension g which, at each extremity, is provided with two guiding rolls Z and Z' and preferably also with an intermediate roll h adapted to roll on the upper face of its respective track and carry the weight of the forward 100 end of the rotary shears. The rear bottom portion of the casting Q is also provided with a roller i having its axis extending towards the cutting end of the shears; said roller serving to support the rear end of the 105 casting as it swings back and forth during its travel under the guidance of the track system aforesaid. The parts are so proportioned and arranged that a vertical line let fall from the cutting point of the cutters 110 will coincide with the miter curve to which the two tracks W and W' are systematically related in the manner disclosed in the foregoing, so that the cutting point will trace a 115 true miter curve during the travel of the 120 casting.

The means for holding the blank of sheet metal U and presenting it to the cutting action of the rotary cutter may conveniently consist of a clamping plate V mounted over 125 the upper table I near the forward margin thereof. This clamping plate may be operated by means of toggles k and l operated from a rock-shaft m which is rotated by a suitable hand lever n. The rock-shaft is in 130

turn journaled in the posts *o* and *p* up-
standing from the table I. The details of
the foregoing elements may be varied widely
to conform to any desired requirements.

5 Without further elaboration, the forego-
ing will so fully reveal the gist of this in-
vention that others can, by applying cur-
rent knowledge, readily adapt it for various
10 applications without omitting certain fea-
tures that, from the standpoint of the prior
art, fairly constitute essential characteristics
of the generic or specific aspects of this in-
vention and, therefore, such adaptations
15 should be and are intended to be compre-
hended within the meaning and range of
equivalency of the following claims.

Having thus revealed this invention, I
claim as new and desire to secure the follow-
ing combinations of features and elements,
20 or equivalents thereof, by Letters Patent of
the United States:—

1. A miter-curve cutting-machine combin-
ing a clamp for sheet-metal; a rotary-cutter;
a supporting carriage therefor providing a
25 first guide and also a second guide widely
spaced apart; a first guide-way coacting
with said first guide; and a second guide-
way coacting with said second guide, said two
30 guide-ways being mutually so contoured as to
cause the cutting point of the rotary-cutter
to trace a true miter-curve and maintain the
cutting plane of said rotary-cutter accurately
tangential to said curve throughout the
35 travel of the carriage.

2. A miter-curve cutting-machine combin-
ing a travelling carriage; a pair of guide-
ways each curved respectively in predeter-

mined relation with the loci of the extrem-
ities of a line of fixed length on said car-
riage travelling tangentially to a miter- 40
curve and with a predetermined point main-
tained in coincidence with said miter-curve;
guiding elements provided by said carriage
to maintain it in such relation to said guide-
ways that the extremities of said line will be 45
maintained in the aforesaid predetermined
relation with said respective guideways; a
pair of rotary-cutters so supported by said
carriage that their cutting plane coincides
with said tangent line and their cutting 50
point vertically over the said predetermined
point; and clamping means for presenting
sheet-material horizontally to said cutters.

3. A miter-curve cutting-machine combin-
ing a travelling-carriage; a pair of rotary- 55
cutters journaled thereon; guiding-elements
spaced widely apart and mounted on said
carriage; a first and a second guide-way co-
operating independently with said guiding-
elements and so curved and disposed as to 60
cause the cutting-points of said rotary-cut-
ters to trace a miter-curve during the travel
of said carriage and to maintain their cut-
ting plane in tangential relation to said
miter-curve throughout the travel of said 65
carriage.

In witness whereof, I hereunto subscribe
my name, as attested by the two subscribing
witnesses.

ALBERT F. NATHAN.
